UNITED STATES PATENT OFFICE.

OSCAR HAYES, OF DENVER, COLORADO, ASSIGNOR TO THE HAYES MANUFACTURING COMPANY, OF DENVER, COLORADO, A CORPORATION OF COLORADO.

VAPOR CREATING AND MIXING DEVICE FOR GAS-ENGINES.

1,244,730.

Specification of Letters Patent. Patented Oct. 30, 1917.

Application filed April 29, 1916. Serial No. 94,451.

To all whom it may concern:

Be it known that I, OSCAR HAYES, a citizen of the United States, and a resident of the city and county of Denver, State of Colorado, have invented certain new and useful Improvements in Vapor Creating and Mixing Devices for Gas-Engines, of which the following is a full, clear, and exact description, such as will enable others skilled in the art to which the invention appertains to make and use the same.

The invention relates to improvements in attachments for gas engines for producing a vapor and mixing the same with the motive fluid; and the invention has for its object the attainment of more efficiency in the use and operation of the engine.

Another object of the invention is to provide means for effecting a more efficient combustion of the motive fluid, and as a consequence, to produce a greater expansion of the fluid after ignition.

Another object of the invention is to provide means for creating a more efficient and volatile motive fluid compound, resulting from mixing in the proper manner volatilized water with the carbonaceous motive fluid.

Another object of the invention is to provide means for producing a more efficient motive fluid, whereby a very great economy in the consumption of the carbonaceous fluid is effected and a greater degree of expansion under combustion created, enuring to the increased motor power of the engine.

Another object of the invention is to provide means for diminishing the collection of carbon in the engine ordinarily incident to the use of carbonaceous motive fluid.

Another object of the invention is to provide means to increase the supply of vapor, whereby the same may be employed for scavenging the cylinders of the engine.

With these and other objects in view, the invention will now be described with reference to the accompanying drawing forming a part hereof.

In this drawing, Figure 1 is a side elevation view of a gas engine, showing the improvement applied thereto; Fig. 2 is a cross sectional view, taken on the line 2—2 of Fig. 3; Fig. 3 is a cross sectional view taken on the line 3—3 of Fig. 1; and Fig. 4 is a detail view of the improvement, show-

ing the lever attachment for operating the same.

Corresponding and like parts are referred to in the following description and designated in all the views of the accompanying drawing by the same reference characters.

Let the numeral 5 represent a gas engine in its entirety. The numeral 6 represents the exhaust pipe of the engine, and the numeral 7 represents the intake, or manifold thereof, the manifold 7 being connected in communicating relation with a carbureter 8 through a passage 9.

A water vaporizing chamber 10 is applied to the exhaust pipe 6 and is in communication with the upper portion of the radiator 12 of the engine through the medium of a pipe 13, through which pipe 13, water is fed from the radiator to the vaporizing chamber 10. The vaporizing chamber 10 is also in communication with the passage 9, from the carbureter 8, through the medium of a pipe 14.

The vaporizing chamber 10 comprises an outer tubular housing 15, having a segmental base 16 integrally formed therewith, which receives and rests against the exhaust pipe 6. The extremities of this base 16 project beyond the housing 15, said extremities being engaged on opposite sides of said housing 15 by means of fastening bands 17, which pass around the exhaust pipe 6 and hold the vaporizing chamber 10 on said exhaust pipe. These bands 17 are brought together at their extremities and fastened, as shown at 18. A valve sleeve 19 is received in the housing 15, and is revolvably mounted therein.

The inner extremity of this valve sleeve 19 is provided with an outwardly extending flange 20, which is formed integral with the said valve sleeve, said flange resting against a shoulder 21, which is formed on the interior of the housing 15. The engagement of the flange 20 with the shoulder 21 serves to hold the valve sleeve 19 against outward movement in a longitudinal direction. A cap 22 is threaded in the outer extremity of the valve sleeve 19 and forms a closure for the outer extremity thereof. The cap 22 is provided with an annular flange 23 thereon, which engages with a shoulder 24 formed on the interior of the housing 15 near the outer

- extremity of the latter. The engagement of this flange 23 with the shoulder 22 serves to prevent the valve sleeve 19 from longitudinally moving in an inward direction.
- 5 The outer surface of the cap 22 lies flush with the outer extremity of the housing 15, whereby a lever 26, which is integrally formed with said cap 22, may be extended beyond the outer surface of the housing 15 at right angles to the latter. This lever 26 is connected with a member 27, which is extended to a position in convenient reach of the operator of the engine. The valve sleeve 19 is operated through the medium 10 of this member 27 and the lever 26 to control the induction of the vapor to the engine. The member 27 is of sufficient rigidity to be pushed backward for operating the valve 19 in the reverse direction.
- 15 One extremity of the pipe 13 is in communication with a port 28 in the housing 15, which said port 28 is adapted to register with a port 29 in the valve sleeve 19. The port 28 of the housing 15 leads through a nipple 30, to the upper extremity of which, the pipe 13 is connected by means of a coupling collar 31, threaded on the nipple 30, as shown at 32. A valve piece 33 is threaded in the nipple 30, as shown at 34, 20 and is adapted to be projected into the port 28 to control the flow of water therethrough into the vaporizing chamber 10. The induction of water into said vaporizing chamber 10 may be entirely shut off by closing 25 the valve, or the induction of water may be regulated by said valve piece 33 in accordance with the amount desired to be admitted to said vaporizing chamber. The pipe 13 is downwardly inclined from the radiator 12 30 to the nipple 30, whereby the water will flow by gravity from the radiator to the vaporizing chamber 10. The upper extremity of the pipe 14 is in communication with a port 35 formed in the housing 15, which port 35 is adapted to register with an eduction 35 port 36 formed in the valve sleeve 19. An air induction port 37 is formed in the housing 15, which is adapted to constantly register with an induction port 38 formed in the 40 valve sleeve 19, the port 38 being of greater length than the port 37, whereby the valve sleeve 19 may be revolved for the purpose of registering the ports 29 and 36 of the said valve sleeve with the ports 28 and 35, or 45 for moving the ports 29 and 36 of the valve sleeve out of register with the last named ports, and at the same time constantly maintain the ports 37 and 38 in register. The ports 29, 36 and 38 are circumferentially in 50 line with each other, and when the valve sleeve 19 is rotated, describe a path intersecting the ports 28, 35 and 37 of the housing 15, which said ports are also circumferentially in line with each other.
- 55 The lever 26 is extended between two stop pins 39 and 40, which are positioned on the outer extremity of the housing 15. We will assume that the lever 26 in Fig. 4 occupies that position there shown when the ports 29 and 36 of the valve sleeve 19 are out of register with the ports 28 and 35 of the housing 15. Now, by pulling on the member 27, the lever 26 will be moved against the stop pin 40, causing the valve sleeve 19 to revolve and register its ports 29 and 36 with the ports 28 and 35 of the housing 15. Thus, water from the radiator 12 will flow through the pipe 13 and pass through the registering ports 28 and 29 into the vaporizing chamber 10. This chamber is at a high 60 degree of temperature under the influence of the exhaust through the exhaust pipe 6, and instantly the water enters the said chamber 10, it will vaporize under the influence of the high temperature within said chamber. 65 The vapor, together with a mixture of air which is taken in through the ports 37 and 38, will then pass from the chamber 10 through the ports 29 and 35 and the pipe 14 into the manifold 7 of the engine, this mixture entering the manifold 7, as well as the cylinders of the engine, forwardly of the induction of the gas from the carburetor 8, the induction extremity of the pipe 14 being in communication with the manifold 7 above the carburetor 8 for that purpose. 70
- 75 By the proper adjustment of the valve 33, the water may be fed into the chamber 10 very slowly, or drop by drop, thereby creating a relatively small volume of vapor 80 to be fed into the engine cylinders.
- 85 The use and operation of the invention, as well as the functions intended to be accomplished, have all been explained in the foregoing description with reference to the 90 structural features of the invention, and it is believed that this description is sufficiently complete and exact, without further description, to enable persons skilled in the art to readily understand the same.
- 95 While I have described and illustrated herein, a specific form of my invention, it is understood that I am not limited thereto and that the same may be modified and varied without departing from the spirit of 100 the invention, or the scope of the appended 105 claims.
- 110 Having thus described my invention, what I claim and desire to secure by Letters Patent is:
1. A device of the class described, comprising a housing, the housing having induction and eduction ports therein, a valve sleeve movably mounted in said housing, the valve sleeve having induction and eduction 115 ports therein adapted to respectively register with the induction and eduction ports of the housing, means for operating said valve sleeve to move said induction and eduction ports of the valve sleeve into and out of reg- 120
- 125

- ister with the induction and eduction ports of the housing, and the housing and valve sleeve having air induction ports permanently in register. 65
5. 2. A device of the class described for attachment to gas engines, comprising a housing secured to the exhaust pipe of the engine, a sleeve revolubly mounted in said housing, a plug received in the outer extremity of said sleeve, said housing having an induction port therein, said sleeve having also an induction port therein adapted to register with the induction port of the housing, the said induction port of the housing being in communication with a source of water supply, the housing and the said sleeve having eduction ports adapted to register, and means establishing communication between said eduction ports and the manifold of the engine. 70
10. 3. A moisture mixing attachment for gas engines, comprising a housing secured to the exhaust pipe of the engine, a valve sleeve revolubly mounted in said housing and forming a vaporizing chamber on the interior thereof, said housing and said valve sleeve having induction ports adapted to register for the reception of water therethrough into the said vaporizing chamber, said induction port of the housing being in communication with a source of water supply, said housing and said valve sleeve also having eduction ports adapted to register for the eduction of the vapor therefrom, means establishing communication from the eduction port of the housing to the cylinders of the engine, and means for controlling the water supply through said induction ports into said vaporizing chamber. 80
15. 4. A moisture injector for gas engines, comprising a housing secured to the exhaust pipe of the engine, a valve sleeve revolubly mounted in said housing and forming a vaporizing chamber on the interior thereof, said housing and said valve sleeve having induction ports adapted to register for the induction of water into said vaporizing chamber, said induction port of the housing being in communication with a source of water supply, said housing and said valve sleeve also having eduction ports adapted to register at the same time the first named ports are in register, means establishing communication between said eduction port of the housing with the cylinders of the engine, the housing having a shoulder on the interior thereof near its inner extremity, the valve sleeve having an annular flange thereon at its inner extremity engaging said shoulder, a plug received in the outer extremity of said valve sleeve and closing the same, said plug having an annular flange thereon, the outer extremity of said housing having a shoulder interiorly formed thereon and engaged by said annular flange of said plug, and a lever operatively connected with the outer extremity of said valve sleeve for revolving the latter to cause its induction and eduction ports to be moved into register, or out of register with the induction and eduction ports of the housing. 85
20. 5. A device of the class described, consisting of a housing, a valve sleeve revolubly mounted in said housing, the housing having induction and eduction ports therein, the valve sleeve having induction and eduction ports therein adapted to respectively register with the induction and eduction ports of the housing, and the housing and valve sleeve having air induction ports adapted to constantly register. 90
25. 6. A moisture injector for gas engines, comprising a housing secured to the exhaust pipe of the engine, said housing having induction and eduction ports therein, a valve movable in said housing and controlling said induction and eduction ports, and the housing having an air induction port permanently open. 95
30. 7. A moisture injector for gas engines, comprising a housing, said housing having induction and eduction ports therein, a revoluble valve sleeve controlling said induction and eduction ports of the housing, means for conveying moisture from the engine into said housing through said induction port, means establishing communication between said eduction port of the housing and the cylinders of the engine, and the housing having an air induction port permanently open to the atmosphere. 100
35. 8. A device of the class described, comprising a housing secured to the exhaust pipe of the engine, said housing having induction and eduction ports therein, a valve rotatable in said housing and having a recess therein, said valve having induction and eduction ports, which, by the rotation of said valve are caused to move into and out of register respectively with the induction and eduction ports of the housing, and means for inducing air into said device. 105
40. 9. A device of the class described, comprising a housing, said housing having induction and eduction ports therein, a valve movable in said housing and controlling said induction and eduction ports, and the housing having a port permanently open. 110
45. In testimony whereof, I affix my signature in the presence of two witnesses. 115
